UNITED STATES PATENT OFFICE.

JOHANNES REITER, OF AIX-LA-CHAPELLE, GERMANY, ASSIGNOR TO CONRAD HEUCKEN, OF SAME PLACE.

COKE-OVEN.

SPECIFICATION forming part of Letters Patent No. 470,506, dated March 8, 1892.

Application filed April 25, 1890. Serial No. 349,428. (No model.)

To all whom it may concern:

Be it known that I, JOHANNES REITER, engineer, of Aix-la-Chapelle, in the Kingdom of Prussia and German Empire, have invented 5 a new and useful Coke-Oven, of which the following is a specification, reference being had therein to the accompanying drawings.

This invention relates to a coke-oven. The ordinary bee-hive ovens employed in the production of coke—that is, ovens of circular form in cross-section and having a domed top—produce the best sort of coke, known as "patent coke," but have the drawback, as compared with other systems of ovens, that they 15 only produce a small output in consequence of the considerable burning away of the coal. This waste results from the inlet of air consequent on these ovens not being hermetically closed during working. Such ovens are usual 20 in England, Pennsylvania, and partly, also, in the mining district of Westphalia. They are also known to some extent under the names of "English" and "Scotch" ovens. In them the process of driving off the gases proceeds 25 from top to bottom within the oven in consequence of air supplied from the outside. Thus, for example, coals having about twenty per cent. of gas produce about sixty per cent. of coke. When such ovens are modified to 30 admit of the recovery of the by-products (tar and ammonia) contained in the oven-gases and are altered so as to effect the hermetic closure necessary for the process of distillation, the gases generated in the ovens and 35 freed in the condensation apparatus from the by-products are led under the floor of the oven for the purpose of heating it. By this modification it has been rendered possible to increase by sixteen to twenty per cent. the output of 40 coke produced in such ovens, which are thus transformed, as it were, into retorts, while obtaining a product of the same quality and commercial value as the coke produced in ovens of the old form; but, since these bee-hive ovens as altered for distillation working 45 are heated from the floor only, the time required for the coking process is considerably greater than in ovens of other systems that are heated both from the floor and sides. 50 The time required for coking in the aforesaid modified ovens is almost double that of the

last-mentioned ovens with the same charge and the same dimensions.

Now the present invention relates to the construction of an oven in which not only fine 55 patent coke can be produced, but in which also the time required for coking is brought down to the reduced amount required for ovens of the more modern systems. This said oven can also be employed for ordinary coking in lieu of the bee-hive ovens of the old form with small output. When it is so employed without any attempt being made to effect the recovery of by-products, the time required for coking is reduced by utilizing 60 the raw and powerful gases generated within the oven. These gases are made to heat the oven from the sides simultaneously with the heating from the floor. Thus there is effected the driving off of the gases and also the complete 65 shutting off of air from the interior of the oven, and in this manner the output is considerably increased.

An oven of this kind is adapted to be employed not only in the production of coke 75 from gassy fat coals, but also from a mixture of dust from dry coals or dust from flaming coals with coal-tar or gas-coals containing sufficient gas for coking. This oven is also adapted for producing coke from briquettes 80 or blocks made from a mixture of coke waste and dust from dry coals or dust from flaming coals with a percentage of coal-tar of six to eight per cent. or fifty-eight per cent. If the content of gas of such a mixture be not 85 sufficient alone to permanently maintain the heating of the sides and the floor of the oven, the oven can be connected with any existing battery of ovens and can take from it the requisite additional quantity of gas necessary 90 for coking.

The drawing of the coke from an oven of this kind is effected by manual labor in a similar manner as in the ordinary bee-hive oven or in bee-hive ovens that have been 95 transformed for the purpose of recovery of by-products, since a drawing-machine is not effective in consequence of the round form of the said ovens. Now, since a drawing operation requires much time, the glowing coke 100 must be cooled by quenching within the oven in order to prevent loss by the burning of the

coke in consequence of the continued influx of air when the oven-door is opened.

For two reasons the circular bee-hive form has been departed from in favor of an elliptical cross-section in which the major axis exceeds the minor axis in length by about one-fourth, as best illustrated in Fig. 1 of the drawings. One reason is that in a circular oven sufficient width of door for the drawing out cannot be readily obtained without interference with the side flues, which occupy the parts of the periphery of the oven that are necessary for the oven-door. Another reason for adopting the elliptical form is to obtain a large area of floor of a larger charging-space. In an elliptical oven the door can be arranged on the side of the oven fronting the major axis at the point where the side flues are situated which are farthest apart and between which there is sufficient space for accommodating the door.

For the construction of the oven it is more convenient to follow not the strict elliptical form but an approximation constructed geometrically by means of circular arcs.

The invention is illustrated by the drawings.

Figure 1 is a horizontal section on line x x of Fig. 3. Fig. 2 is a plan view of the dome, 30 showing the division-walls and central flue in section. Fig. 3 is a section on line A B of Fig. 1. Fig. 4 is a side elevation. Fig. 5 is a section on line C D, Fig. 1. Fig. 6 is an elevation with a portion of the outer wall removed. Fig. 7 is a view in section of the exit flues.

As shown in Fig. 1, the space below the floor of the oven is divided by a partition x , following the direction of the major axis, into two 40 equal parts with no direct communication. Each of these parts has floor-flues r or r' , each connecting with one of the side flues a , b or A B, &c. There are thus below the oven-floor fourteen flues of equal width and height, 45 which are in communication with lateral flues a , b , A, B, leading upward along the side walls of the oven, these being of unequal width, the width increasing with their respective distance from the major axis. In the intermediate space between the two side flues that are farthest from the major axis there is 50 at the front of the oven space for an oven-door opening S. This space does not interrupt the communication of the two side flues 55 A, situated next to this opening, with the floor-flue r .

As shown in Figs. 3 and 5, an outer inclosing wall is provided above the oven-dome, forming an arched space between it and the 60 said wall, and this space is divided into three chambers by division-walls t , x' , and z , the side flues opening into these chambers. This arched space is for the reception of the gases generated within the oven. These gases enter 65 it at one part through an opening y , Fig. 2, provided in the oven-dome, and pass down the side flues a to g into the floor-flues r , r' . They then

rise through other side flues A to G into one part of the space or chamber T, passing from thence, as shown by the arrows, down flues o 70 to p , through the floor-flues r , r' , up through the side flues H to R into another part of the chamber T, and from thence to the exit-flues M, N, which connect with the flues u , u' , leading to the chimney. It will be understood that 75 the division-walls t , x' , and z cause an interruption of the direct circulation and make it circuitous, as described.

The gases passing from the inside of the oven into the gas-flue are arrested in their 80 course by the second partition z . They accumulate and are compressed and are obliged to flow through the side flues a to g , inclusive. They then pass through the floor-flues r from 85 a to g , and rising up through the side flues A, G, they reach the opposite side of the flue and are thereby accumulation and compression by means of the third partition t again obliged to continue their course downward through the side flues h , o and through the floor-flues r' of h , o . Then again rising up through 90 the side flues H, T, K, L, O, P, R they again reach the opposite side of the flue, where in their further course they are again caused to accumulate and be compressed by the 95 third partition t , and are thereby obliged to escape down through the side flues M and N into the collecting-flue u on their passage to the chimney.

All the floor-partitions, with the exception of 100 the central partition x , are formed in the half of their length through which the floor-gases first pass with one or more openings a' or interruptions. These openings are designed to produce a uniform distribution of the gases 105 in the several floor-flues, and thus to compensate for the non-uniform width of the side flues and consequent non-uniform density of the gases passing through the side flues.

In the niche or recess Y, situated above the 110 vault W of the door, there are provided on each side two openings 1, 2, 3, 4, capable of being closed, of which the opening 1 is designed to allow of observation of the gases passing down or up in the side flues (on the left No. 115 1 for the descending gases, on the right No. 4 for the ascending gases) and the other opening 2 or 3 for the observation of the gases circulating in the chamber. Observation-ports may be provided for the other portions of the 120 space T.

What I claim, and desire to secure by Letters Patent of the United States, is—

1. A coke-oven having a central chamber, a series of parallel flues beneath the floor 125 thereof, arranged in two sets, a series of wall-flues connecting with the parallel flues and opening into the space above the dome, division-walls in said space, and a door opening to said central chamber above the line of the 130 floor-flues.

2. A coke-oven having a central chamber, a series of parallel flues beneath the floor, arranged in two sets, openings in the walls of

each set, an imperforate division between the sets, wall-flues, a space above the dome in communication with the wall-flues, and division-walls in said space, substantially as described.

3. A coke-oven consisting of an outer inclosing shell or wall, a dome-shaped oven within the same, a series of flues along its sides, floor-flues communicating therewith, a space above the dome, division-walls in said space, an opening from the oven proper to one of the

compartments above the dome, and exit-openings leading to the chimney from another compartment above the dome, substantially as described.

15

In witness whereof I have hereunto set my hand in presence of two witnesses.

JOHANNES REITER.
